CLAIM

I claim the ornamental design for a monofin for swim training, as shown and described.

DESCRIPTION

FIG. 1 is a top perspective view of a monofin for swim training, showing my new design;

FIG. 2 is top plan view thereof;

FIG. 3 is a front plan view thereof;

FIG. 4 is bottom plan view thereof;

FIG. 5 is a back plan view thereof;

FIG. 6 is a left side plan view thereof; and

FIG. 7 is a right side plan view thereof; and,

FIG. 8 is a top plan view with unlatched strap thereof.

1 Claim, 5 Drawing Sheets
